UNITED STATES PATENT OFFICE.

JOHN WILLIAM LAMBERT, OF ANDERSON, INDIANA.

TRACTOR-TREAD.

1,290,586.

Specification of Letters Patent.

Patented Jan. 7, 1919.

Application filed December 11, 1917. Serial No. 206,599.

To all whom it may concern:

Be it known that I, JOHN WILLIAM LAMBERT, a citizen of the United States of America, and a resident of Anderson, county 5 of Madison, and State of Indiana, have invented certain new and useful Improvements in Tractor-Treads, of which the following is a full and clear specification.

The object of this invention is to simplify 10 and improve the tread structure covered by the Fuller and Lambert Patent No. 1,241,617 dated October 2, 1917, in which each tread-plate carries a pair of transverse links rigidly fastened to the tread-plates transversely 15 of their inner faces in an edgewise upright position, a series of connecting links being provided between the tread-plates; and the special object of the present invention is to provide a more inexpensive and more durable 20 and rigid link arrangement on the tread-plates, as more fully hereinafter set forth.

In the drawing, *a* designates the flat tread-plates on the inner faces of which is formed 25 a pair of transverse depressions *b* which terminate short of the longitudinal edges of the plates in upwardly-rounded ends *c*, these depressions being arranged one near each end of the plate. Fitting down in each of these 30 depressions is the lower bar of a link *d*, this link being set edgewise upright on the plate and having rounded ends which fit against the rounded end *c* of the depression or groove *b*.

The top side of the link *d* is open, at *e*, so 35 that this link may be conveniently formed by simply bending over and inwardly the edges of the flat bar. Bridging the opening *e* is metal block *f* which fits between the lower solid bar of the link and the upper 40 split or divided bar of the link, suitable bolts *g* being employed to clamp the bar or block *f* rigidly within the link and the link itself to the tread-plate, one of these bolts extending 45 down through each of the free ends of the top bar of the link, through the intermediate block *f*, the bottom bar of the link, and the tread-plate. The ends of the rigid link *e* terminate approximately at either of 50 the longitudinal edges of the tread-plate, and the adjacent links are pivotally connected together by horizontally-arranged links *h*, the ends of the filler-bars *f* serving as abutments for the cross-bars *i* of these 55 links *h*, so as to thereby properly space the

tread-plates with respect to each other. On each of the plates, at a point midway between the ends thereof, is provided a sprocket-tooth *j*.

It will be understood that the slot *b* may 60 be omitted, so that the link *d* will lie directly on the surface of the tread-plate, and it will also be understood that separable or sectional links may be employed in place of the solid links *h*. It will be seen also that the construction is such that I am enabled to use a very large sprocket tooth *j*, so as to render this tread appliance adapted for use on rollers or wheels of a large diameter, thereby materially reducing the pressure and strain on 65 the sprocket devices. It will be observed further that a feature of importance lies in the fact that the tread may be separated at any one of the joints between the tread-plates by simply removing the spacing block 70 *f* and then slipping the adjacent end of the link *h* out through the opening *e*, thereby rendering a pair of these tread appliances very easily made at any point in its length. It will be seen also that two pairs of these 75 appliances are further provided for making the tread plates quickly detachable from the links.

The nature and scope of the invention having been thus indicated and its preferred 80 embodiment having been specifically described, what is claimed as new is:

1. A tractor tread comprising a series of plates each of which is provided with a sprocket-tooth as well as a pair of transverse grooves on its inner face, a link having its lower bar fitted in each of said grooves, means for rigidly fastening said link edgewise upright on the tread-plate, and connecting links. 90

2. In a tractor tread, a series of tractor tread-plates each provided with a sprocket-tooth and also with a pair of transverse grooves in its inner face, a link having its lower bar fitted in each of said grooves, the 100 top bar of the link being divided, a filler-block fitting within the link, bolts extending down through the free ends of the top bar intermediate the filler-block, the lower bar of the link and the tread-plates, and connecting links.

3. A tractor tread comprising a series of plates each of which is provided with a sprocket engaging means, a transverse link rigidly bolted to each tread-plate; each of 110

these links having an opening at one side about midway its length, and connecting links between the aforesaid links.

4. In a tractor tread, a series of tractor tread-plates each provided with a sprocket tooth, a pair of links each having its lower bar removably fastened to the face of each of said plates, the top bar of each link being provided with an opening, a filler-block fit-

ted within each link blocking said opening, 10 bolts extending down through the free end of the top bar of the link, the intermediate filler-block, the lower bar of the link and the tread-plate, and connecting links.

In testimony whereof I hereunto affix my 15 signature.

JOHN WILLIAM LAMBERT.
